SOAKING-PIT TROLLEY

Christopher Henry Schramm, Muskegon, Mich.,
assignor, by mesne assignments, to Manning,
Maxwell & Moore, Inc., New York, N. Y., a cor-
poration of New Jersey

Application September 28, 1935, Serial No. 42,645

1. Claim. (Cl. 268—10)

The object of this invention is to provide a combined hoisting and traversing mechanism especially adapted to raise, lower and traverse the fire-brick cover of a high-temperature furnace of the floor-installed type for heating ingots in steel mills.

In the prior art the cover of a soaking pit was attached to a machine or carriage running upon rails some three feet above the floor. The carriage was not provided with any hoisting mechanism, the cover being raised and lowered by providing declivities in the rails. When the carriage rolled down the declivities the cover was lowered onto the top of the furnace. Being thus lowered sidewise onto the furnace and traveling, as it did, a distance of about two feet during the lowering operation, it was impossible to provide a seal around the furnace opening. Because of the absence of a seal, the brickwork of the furnace was exposed to spalling and distortion, so that in a short time openings were produced through which intense heat was radiated. The uneven application of heat in the furnace, due to the loss of heat through openings around the furnace throat, caused uneven heating of the ingots and compelled the workmen to rearrange the ingots in the furnace by means of the overhead electric ingot-handling crane commonly provided for that purpose. Moreover, the heat escaping through the openings around the furnace throat caused rapid destruction of the metal parts binding the furnace together and produced warping of the cast steel rails on which the carriage operated. This manner of removing and replacing the cover resulted in great loss of heat, damage to the rails upon which the carriage moved, disorder and delays in production, and danger to the workmen.

By means of the present invention an effective seal is provided at the furnace throat, thus conserving heat, eliminating the rapid deterioration of rails and other structures heretofore experienced, improving the quality of the ingots, promoting increased efficiency of the operating personnel, and reducing operating costs.

In the accompanying drawings

Figure 1 is a perspective view of a soaking pit trolley embodying the features of my invention.

Fig. 2 is a plan view of the trolley, the cover being indicated by a dotted circle.

Fig. 3 is a fragmental end elevation of the trolley in operative relation to a soaking pit.

Fig. 4 is an elevation of that side of the trolley on which the hoisting motor is mounted.

Fig. 5 is an elevation of the opposite side of the

trolley namely, that on which the traversing motor is located.

In Fig. 3, *a* indicates the floor level, *b* the throat of the soaking pit, *c* an annular recess in the floor encircling the throat of the soaking pit, said recess being filled with sand, and *d* the cover of the pit, said cover having a flange *e* adapted to be embedded in the sand when the cover is in closed position to form a seal.

Rails *f* are mounted on the floor at opposite sides of the furnace. These rails extend far enough away from the furnace so that the cover may be removed laterally sufficiently to uncover the throat *b* and as much farther as may be desired.

The trolley comprises a rigid frame of generally rectangular form consisting of two girders *1* and *2* and two transverse beams *3* and *4*. This frame is provided with rollers *5* that run on the rails *f*. The rollers *5* at one end of the frame are arranged to be driven by means including a transverse shaft *6* journaled on the girders *1* and *2*. Drive chains *7* communicate power from sprocket wheels on the shaft to sprocket wheels fixed on the axles of said rollers. The shaft *6* is driven through bevel gears *8* (Fig. 2) from a shaft *9*, the latter being connected through a speed reducer *10* and a flexible coupling *11* to an electric motor *12*. *13* is a magnetic brake of any desired construction for stopping the motor and thus arresting the travel of the trolley.

The cover *d* may be suspended from the trolley at four equidistant points by any suitable means, as, for example, lugs *g* (Fig. 2) fastened to the cover. These lugs have a pin-and-slot connection, as shown in Fig. 3, to swiveling clevises *14*. The latter are connected to rockers or bell cranks *15* and *16* which are pivoted at *17* in the beams *3* and *4*. The pair of rockers on the beam *3* are connected to move together by means of a reach *18*, the rockers on the beam *4* being similarly connected. In order that all four rockers shall swing in unison, the rockers *16* are connected through pitmen *19* (Figs. 2 and 3) to a crank shaft *20* journaled in the beams *3* and *4*. The shaft *20* is located at one side of the throat of the soaking pit, hence its bearings are some distance from the throat of the pit and thus somewhat removed from direct exposure to the heat. The crank shaft is driven through gears *21* from a shaft *22*. Power to drive the shaft *22* is obtained from an electric motor *23* through a flexible coupling *24* and a speed reducer *25*. A magnetic brake *26* serves to stop the motor *23* when the cover has been raised or lowered, said brake *26*

- assisting to hold the cover elevated after it has been raised. A rotary type limit switch (not shown) of any preferred construction may be connected to the crank shaft 20 and adjusted to 5 interrupt the circuit of the hoist motor 23 at the extreme points of crank throw, i. e., when the cover has been lifted to full height and when the cover has been allowed to rest on the sand seal.
- 10 A limit switch 27 (Fig. 5) connected into the circuit of the traversing motor 12 and located adjacent to the soaking pit is arranged to be engaged by a cam 28 on the trolley as the latter reaches such a position that the cover *d* is directly 15 over the pit, thereby stopping the traversing motor in that position.
- It will be seen that the construction herein disclosed eliminates all overhead apparatus, with the dangers incident to the use and maintenance 20 of such apparatus; that the trolley is so constructed as not to be damaged by the high temperature conditions to which it is constantly exposed; that the cover *d* is directly beneath and approximately enclosed by the trolley and is 25 raised and lowered and moved horizontally fixed distances without attention on the part of the operator; that excessive pressure cannot be placed upon the cover when the latter is lowered onto its seat, as the cover has a floating connection 30 with the trolley; and that by the use of conventional electric switches the trolley may be easily and safely controlled to raise, remove, return and lower the cover without exposing the operator or other workmen to danger.
- 35 In prior-art instances wherein the cover was moved by a carriage, special apparatus was provided at one side of the soaking pit for supporting and traversing the carriage. The driving motor was stationarily located along or near the path of

travel of the carriage. This arrangement entailed loss of space in the building and placed limitations upon the location of the pits, it being understood that in practice a number of soaking pits must be accommodated in the building and provided with cover-handling means.

My apparatus is compact and self-contained, the motors that raise, lower and traverse the cover being mounted on the carriage. Thus the apparatus occupies a minimum amount of space 10 and does not necessitate any uneconomical arrangement of the pits.

I claim as my invention:

The combination with a soaking pit of the floor-installed type having a cover adapted to rest 15 upon the floor, of rails located on the floor at opposite sides of the pit, a trolley mounted on said rails and adapted to be traversed from a position directly over the pit to a position at one side thereof, said trolley comprising two girders 20 disposed parallel to respective ones of said rails, roller means on said girders engaging the rails to support the trolley thereon, and two transverse beams connecting the ends of said girders to form a rigid rectangular frame, means on the trolley 25 for raising and lowering the pit cover comprising a pair of bell-crank levers pivotally supported on each of said beams and removably connected with the pit cover, means connecting each pair of bell cranks together for simultaneous operation, a 30 shaft extending across the trolley and journaled on said beams, crank arms mounted on said shaft adjacent said beams, each crank arm being connected with one of said bell crank levers whereby to rock the levers and thereby raise and lower the 35 pit cover in response to the rotation of the shaft, and means including a motor mounted on one of said girders for rotating said shaft.

CHRISTOPHER HENRY SCHRAMM.
